UNITED STATES PATENT OFFICE.

JAMES RETTIE, OF LONDON, ENGLAND.

CATCH AND ESCAPEMENT-GEAR.

SPECIFICATION forming part of Letters Patent No. 774,198, dated November 8, 1904.

Application filed February 16, 1903. Serial No. 143,679. (No model.)

To all whom it may concern:

Be it known that I, JAMES RETTIE, engineer, a subject of the King of Great Britain, residing at 191 Camberwell road, London, England, have invented a new or Improved Catch and Escapement-Gear, of which the following is a specification.

This invention consists of a series of toothed wheels, shafting, bearings, supports, and connections designed and constructed to act in the manner and for the purpose of ratchet-gearing without the detrimental slip and uncertainty of action in all gears of that description constructed on the hitherto-recognized principles of such mechanism. It is intended to apply generally to all classes of machinery for which a smooth-working continuously-gearred catch-and-escape movement is a desideratum.

The main principles of the above can be carried out in various forms, having suitably-different constructive and positional arrangements to meet requirements in its adaptation to machines of dissimilar utility, and in order to demonstrate more effectually the essential points which constitute my invention and the manner of its action I have herewith furnished a set of drawings which illustrate some of the modes of adjustment which I adopt in its practical application to purposes for which it is designed.

Referring to the accompanying drawings, Figure 1 shows a form of adjustment of three of the main factors in my invention, which are denoted throughout the drawings by letters A, B, and C, A being a screw-toothed pinion made on or fitted on to a shaft L, on which B, a double-thread worm, is formed with a pitch the same as the screw-teeth on the pinion A, but out of run with them to the extent of about the thickness of the worm-thread. C is a skew-toothed spur-wheel or circular rack with which the screw pinion and worm gear in the manner shown. The spaces between the teeth on the wheel C and those which form the channels between the worm-threads are about twice as wide as the teeth are thick.

Fig. 2 gives a face view of the skew-toothed spur-wheel C, mounted on a shaft D, by which

motion given to the wheel it carries is conveyed to the point of its utility.

Fig. 3 is a front elevation of a bracket or standard having a hole 12 bored in it to receive and act as bearing to the shaft D, Fig. 2. It also provides two projecting lugs F F', 55 which are intended to carry the worm-shaft L', Fig. 5, and a boss E', which carries a stud H, on which the spur-pinion J, Figs. 9 and 10, is to operate.

Fig. 4 is a side view of Fig. 3 and its projections.

Fig. 5 represents a screw-toothed pinion, shaft, and worm similar to that shown in Fig. 1, with the worm-threads B' running reversely and the screw-pinion A' having a parallel in 65 lieu of a conical outer diameter.

Fig. 6 shows a collar and pin K and K', which are formed to fit on the pierced end 13 of the worm-shaft L', Fig. 5, to secure it in its intended working position.

Fig. 7 presents a side view, and Fig. 8 a front view, of a rocking lever G, in which a hole 14 is bored to fit the shaft D, Fig. 2, on which the said lever is intended to work. That portion of the lever G immediately above 75 the hole 14 is formed into a cradle to carry the shaft L, Fig. 1, and the pinion A and the worm B combined with it by means of a pair of lugs G' G'', Fig. 7, which are bored at the points indicated by dotted lines 15 and 16, 80 Fig. 8, to receive it. These lugs are connected by a bridge 17, on which the handle-bar 18 is either made or fitted.

Figs. 9 and 10 give a side and face view of a spur-pinion J, which is intended to work on 85 the stud H, Fig. 3.

Fig. 11 shows an apparatus composed of the parts hereinabove described, and shown in Figs. 1 to 10, inclusive. It is designed specially to illustrate the manner in which my 90 invention can be utilized as an auxiliary in transmitting motion and retaining gathered tension or accumulated force.

Fig. 12 is a piece of mechanism designed to illustrate the manner in which I apply a releasing action to either the propelling or retaining portions of the apparatus shown in Fig. 11.

Fig. 13 shows one of the many ways in which the positional arrangement can be varied and constructive changes made in the parts A, B, and C of my invention without departing from 5 the principle thereof.

Fig. 14 illustrates the manner in which my invention (in a modified form) can be employed as an instantaneous catch-and-release gear in connection with hoisting and lowering appa- 10 ratus and such like machinery.

Fig. 15 is a sectional view of the loop-frame E, Fig. 14, in which the gear which operates between the spur-wheel C and beveled pinion W in the same figure is shown.

Referring to Fig. 1, it will be noticed in the 15 gearing of the same that where the pinion A gears with the spur-wheel C the teeth of the former bear on the right-hand sides of the teeth of the latter, which are numbered 1 and 2, and leave spaces 6 and 7 between their backs and the teeth numbered 2 and 3, while the 20 worm-threads 10 and 11 are shown bearing on the left-hand sides of the spur-teeth 4 and 5, leaving spaces 8 and 9 between themselves and 25 the spur-teeth 3 and 4. By the above arrangement in the gearing of the combined worm and screw-pinion B and A, respectively, and the spur-wheel C it will be plain that in any movement of wheel C in the direction of the 30 arrow Z its teeth would strike the worm-threads only, in which case the slanting run of the worm B would allow it to easily rotate the combined worm and pinion and make a free passage for itself through the screw- 35 teeth of the pinion A, which would rotate idly in gear during the movement; but in any attempted move of the wheel C in the opposite direction its teeth would only come in contact with the screw-teeth of the pinion A, and 40 these would act to it as an absolute stop, because they are too squarely set to permit the wheel C to force the pinion A into revolution.

The above and Figs. 2, 3, 4, 5, 6, 7, 8, 9, and 45 10 constitute the component parts of Fig. 11, which illustrates a form of my invention constructed to effect the double purpose of giving rotary motion to the shaft D in one direction and preventing similar movement of the same in the other. The movement and rest of the 50 shaft D can of course be utilized in any suitable manner and for any suitable purpose. In the performance of this operation the rocking lever G is moved in the direction of the arrow X, when the worm-teeth 10 and 11 strike 55 the teeth 4 and 5 of the spur-wheel C (which is held stationary by the screw-pinion A') and by them force into revolution the worm-shaft L and screw-pinion A, which causes the latter to rotate smoothly through the teeth with 60 which it gears in the direction named; but when a return action of the lever is made the pinion A becomes an effective catch in the teeth of the wheel C and forces it around in the direction of the lever's travel, as the spur-

wheel cannot cause the pinion A to rotate 65 without the assistance of the worm B, and that is rendered inoperative by the spacial distances which intervene between its threads and the spur-teeth in advance of them. Thus a backward-and-forward movement of the lever G gives motion to the wheel C and shaft D in the direction of the arrow Z. Now when motion is given to the wheel C in the manner described above the movement is transmitted through the spur-pinion J to the worm B' and 70 shaft L', and the screw-pinion A' thus rotated allows a free travel to the wheel C in the direction of the arrow Z, but prevents any back movement of the same by reason of the proportional formation of the spur-teeth and 75 worm-threads and the distances between them, which are similar to those described, and shown in Fig. 1.

I have by preference shown the above-described mechanism as driven by hand. It 85 will, however, be obvious that by detaching the hand-lever 18 from the cradle G and making suitable connection between the latter and any moving force the same result could be obtained, and, further, that by the employment 90 of two or more such apparatus on the same shaft and actuating them alternately a constant in lieu of an intermittent motion could be produced and regulated as regards speed in various ways without interfering with the 95 main principles of the invention.

It will be observed that in the above-described form of my invention no provision is made to allow a reverse movement of the 100 wheel C. It can, however, be furnished with such in the manner shown in Fig. 12, in which the parts A, B, and C are geared in the same way as the similarly-denoted parts in Figs. 1 and 11; but in this case the worm-shaft L is mounted in three bearings F F' F'', formed on 105 a bracket M, which is fitted on the shaft D and provides the outstanding arm N. Near one end of the shaft L a circular groove is sunk, in which an annular plate 20 (shown in section) is fitted. This plate is bolted to a hand-wheel 110 O, also shown in section, which is carried by and operates the screwed spindle 21, (shown in position in the boss N' of the arm N.) The screw-pinion A is fitted on the worm-shaft L with a feather in such manner that it will 115 slide freely along it, but must turn with it between the bearings F and F', where it is shown geared with the spur-wheel C. When the above parts are in the position shown, the 120 wheel C can only turn in the direction of the arrow Z; but by turning the hand-wheel O and moving it forward on its screwed spindle 21 the worm-shaft L is forced along in its bearings and the worm-threads made to strike the spur-teeth at the other side of the spaces, 125 and thus cause the worm B to operate the screw-pinion A in a backward direction and allow a free return travel to the spur-wheel

C, the speed of which can be regulated or its stoppage effected at any desired moment by manipulating the hand-wheel O.

Fig. 13 is another form of my invention which I think it advisable to show, in which D is an upright shaft on which is mounted a spur-wheel C, which is also provided with crown ratchet-teeth C' on its upper side, with which the screw-pinion A engages in the manner shown. This said pinion A is carried on a spindle L, on which is formed the skew-toothed pinion B, which gears with the wheel C and in action rotates the pinion A, which follows up any movement of the wheel C in the direction of the arrow Z and acts as a rotating pawl to prevent any back movement of the wheel with which it gears. The shaft D and spindle L can be mounted in bearings in the position shown and fixed as the occasion may require. The teeth and the spaces between them on the skew-toothed pinion B and spur-wheel C are proportioned similar to those described in Fig. 1.

Fig. 14 illustrates a form of my invention which can be utilized as a safety catch-gear for cranework and the like. Here D is the main axle, C is a spur-wheel made fast on it, and C' a skew-tooth catch-wheel made solid with the spur-wheel C or firmly secured to it. E is a loop-frame which forms a carrier for a spindle Q, which bears the combined beveled wheel R and spur-pinion S in the manner shown in Fig. 15, where the loop-frame E is shown in cross-section. The spindle Q is possessed of a square enlargement 28, Fig. 15, which is bored through at right angles to the spindle to form a bearing for one end of the shaft L, which carries the beveled pinion W and is fitted to work in the position shown by dotted lines 29. The other end of the shaft L, which bears the screw catch-pinion A, is provided with a semiglobular socket, which takes a spherical roller 30, which bears against the frame E in an elongated recess (shown by dotted lines 31) and forms a movable point of resistance to the shaft L and its attachments. Encircling the end of said shaft outside the socket and roller 30 is a collar, which forms one end of a connecting-rod T, which passes up through the frame E, the upper end of it taking an eccentric 32, which is fitted on the end of a bar U, which is fitted to work in bearings formed on the frame E and shown at points 33 and 34. A handle V is formed on the outer end of this bar to operate it. The bored lug 35, made on the frame E, is provided for fixing it and holding it to its work. The gearing of the wheels C, S, R, and W when in work is as follows: The pinion S, Fig. 15, gears with the spur-wheel C, having a close-fitting but easy-working travel. The beveled wheel R and the beveled pinion W, which have spaces between their teeth by preference twice as wide as the

teeth are thick, are geared to drive off one side of their teeth only during the time the screw-pinion A is in gear with the catch-wheel C'. The consequence is that when movement is given to the spur-wheel C in the direction of the arrow Z the pinion A is rotated in agreement with the movement of the catch-wheel C' and a smooth unrestricted motion obtained. Any backward motion, however, of the above-named parts is prevented by the pinion A, which cannot be rotated reversely when in gear on account of the formation of teeth and spaces on the beveled wheel and pinion R and W. When reverse movement of the mechanism is required, it is only necessary to turn the bar U in its bearings, when the eccentric 32 will lift the connecting-rod T, and with it the catch-pinion A, clear of the gaps in the catch-wheel C', and the whole of the parts can travel backward. The screw-teeth of the catch-pinion A during this action remain constantly over the gaps in the catch-wheel C' and can be instantaneously struck back in gear and an immediate stop to the back movement effected.

It will be readily understood that the above and previous described forms of my invention represent but a small proportion of the different ways in which it can be adapted to the many classes of machinery to which such a mechanism is a necessary adjunct. Therefore I reserve the right to such further variations and modifications as properly fall within the scope of my invention, which must be regarded rather in the character of an auxiliary equipment to machinery in which such a gear is a necessary constituent part than as an entire machine in itself, and as such the extent of its applicability cannot be fully demonstrated by the few examples herein described, and illustrated in the accompanying drawings; but I consider what I have described and shown sufficient to explain the nature and purpose of my invention, which is essentially a substitute for ratchet-and-pawl mechanism possessing the important advantages of certain and instantaneous action, which is obtained by the employment of the rotary slip and catch wheel A A', geared to operate with a straight, curved, or circular rack or ratch, assisted by the worm B B' or its equivalent in the manner herein specified in lieu of the ordinary pawl.

Having thus fully described my invention, what I claim is—

1. In catch and escapement-gear, or the like, a rotating catch, formed of a metal pinion provided with a worm, on its periphery, a shaft, on which it is fitted, mounted revolubly in bearings, a contrivance providing the said bearings, a rack, the catch and rack being geared worm-and-wheel fashion, the catch adapted (when not rotated) to deliver movement, or act as a detent to the rack, and when

rotated allowing travel to the same, means to insure rotation of said catch in harmony with required movement of the rack, all combined to operate substantially as set forth.

- 5 2. A rotating catch, consisting of a metal pinion provided with a worm on its periphery, combined with a second worm or spiral groove, of similar pitch but smaller diameter, a shaft, on which it is fitted, and mounted therewith 10 revolubly in bearings, an oscillating lever providing said bearings, pivotally connected to a second shaft, the second shaft, mounted in a suitable bearing at right angles to the axis of the rotating catch, a skew-toothed wheel or 15 circular rack, mounted on the second shaft, with which the rotating catch and worm are geared worm-and-wheel fashion, the said catch serving to compel movement of the circular rack when the rocking lever is moved in one 20 direction, and the worm combined with it serving to produce rotative escape for the catch in the other direction, whereby the rack is free to continue the movement delivered to it by the catch after the propelling action of the 25 latter has ceased, and the rocking lever to effect its return movement and repeat its previous action, means to prevent any return movement of the rack, during return action of the rocking lever, substantially as described.
- 30 3. In catch and escapement-gear, or the like, a rotating catch, consisting of a metal pinion provided with a worm on its periphery, a shaft bearing a second worm, on which the said catch is fitted, and mounted therewith revolubly in 35 bearings, a bracket providing said bearings, and also a bearing to carry a second shaft at right angles to the axis of the catch and worm, the second shaft journaled in said bearing, a

skew-tooth wheel or circular rack secured thereon, with which the rotating catch engages worm-and-wheel fashion, and serves when stationary in its bearings, to prevent rotative movement of said rack, means to effect rotation of said catch, whereby the release of the rack is effected and its travel permitted, substantially as set forth.

4. In catch and escapement-gear, or the like, a rotating catch, consisting of a metal pinion, provided with a worm on its periphery, a shaft on which a second worm is formed, and on which the rotating catch is splined, so that it can move longitudinally on it, and will turn with it, the worm on the said shaft, a bracket providing bearings for said shaft, which is mounted revolubly therein, a second shaft, for 50 which said bracket also provides a bearing, in which the said shaft is journaled at right angles to the axis of the shaft carrying the rotating catch, a skew-toothed wheel or circular rack, mounted on second shaft, and having rotative travel therewith, and geared worm-and-wheel fashion with the rotating catch and second worm, means to effect longitudinal movement of the first-mentioned shaft, and thereby put the second worm in or out of operative relation with circular rack, whereby the rotating catch can be caused to prevent, or permit, rotative travel of said rack, substantially as specified.

In testimony whereof I have hereunto set my hand, in presence of two subscribing witnesses, this 4th day of February, 1903.

JAMES RETTIE.
